UNITED STATES PATENT OFFICE.

PATRICK C. CANFIELD, OF ASHTABULA, OHIO.

PLASTERER'S HOE.

SPECIFICATION forming part of Letters Patent No.317,502. dated May 12, 1885.

Application filed May 31, 1884. (No model.)

To all whom it may concern:

Be it known that I, PATRICK C. CANFIELD, a citizen of the United States, residing at Ashtabula, in the county of Ashtabula and State of Ohio, have invented certain new and useful Improvements in Plasterers' Hoes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention has reference to an improvement in hoes, more especially such as are used by plasterers, having for its object to effect the thorough mixing of the mortar by comminution, the intimate intermixture of the substances being thus effected; and the invention consists of the detailed construction of the blade, substantially as hereinafter more fully described and claimed.

In the accompanying drawings, Figures 1 and 2 are a front and a rear view, respectively, of my invention. Fig. 3 is a perspective view of the same.

Similar letters of reference in the several drawings denote like parts.

In the embodiment of my invention I construct the blade A in all respects, except as hereinabove pointed out, of the usual construction. The tang B is made integral with the blade, forming a tapering thickened-up central portion or rib, b, upon the rear side of the blade, said rib extending from a little below the middle of the blade upward and over the top edge of the blade, thereby re-enforcing the blade where the greatest strength is needed, and to compensate for the weakening of other parts arising from the further construction of the blade, as will be presently described.

It is a well-known fact that upon bringing an inflexible or unyielding substance into forcible contact with a yielding substance, or one incapable of resisting the blow or force of the other, should the first present a broken or perforated surface to the latter, the particles of said latter substance will be forced through the apertures or perforations of said former substance, whereby the unresisting material or substance will be divided up or comminuted, and the same be more thoroughly acted upon, thereby securing the best possible results. With this end in view I have provided the blade A with apertures or perforations C C, one being disposed upon each side of a vertical plane passing through the rib or thickened portion forming an extension of the tang. In addition to this result, it greatly facilitates and lessens the labor of thoroughly working up and mixing of the mortar.

I am aware that it is not new to make a weeding-hoe with an opening in the center of the blade to prevent earth from adhering thereto.

Having thus fully described my invention, what I claim, and desire to secure by Letters Patent of the United States, is—

The hoe-blade A, having its central portion re-enforced by a rib, b, a continuation of the tang, and provided with perforations or apertures C C, one arranged upon each side of a vertical plane passing through said rib or thickened portion of the blade, substantially as shown, and for the purpose set forth.

In testimony whereof I affix my signature in presence of two witnesses.

PATRICK C. CANFIELD.
